United States Patent Office

Des. 202,024
Patented Aug. 24, 1965

202,024

BOUDOIR CAP

Lillian Gettinger, 2509 Shelley Dale Drive,
Baltimore, Md.

Filed Oct. 7, 1963, Ser. No. 76,882

Term of patent 7 years

(Cl. D3—13)

FIG 1

FIG. 2

FIGURE 1 is a perspective view of a boudoir cap embodying my new design, with the rear thereof being substantially similar in appearance thereto; and

FIGURE 2 is a perspective view of a boudoir cap with the adjusting ring removed.

I claim:

The ornamental design for a boudoir cap, as shown and described.

References Cited by the Examiner

UNITED STATES PATENTS

1,598,379 8/26 Kerr.

2,552,803 5/51 McGee.
2,579,089 12/51 Price.

OTHER REFERENCES

Notion and Novelty Review, February 1963, page 61, cap shown on right, 2nd from top.

Notion and Novelty Review, May 1, 1962, page 37,
Karaway cap shown bottom left of page.

EDWIN H. HUNTER, Primary Examiner.

LOUIS J. PERLSTEIN, Examiner.